UNITED STATES PATENT OFFICE.

ALBERT G. ELVIN, OF SOMERVILLE, NEW JERSEY.

FIRE-DOOR APPARATUS.

1,190,528.

Specification of Letters Patent.

Patented July 11, 1916.

Application filed September 25, 1914. Serial No. 863,451.

To all whom it may concern:

Be it known that I, ALBERT G. ELVIN, a citizen of the United States, and a resident of Somerville, in the county of Somerset and State of New Jersey, have invented a certain new and useful Improvement in Fire-Door Apparatus, of which improvement the following is a specification.

This invention relates to apparatus for operating doors of boiler furnaces, and particularly to fire doors for locomotive boilers, the principal object being to provide an improved combined fluid pressure and hand operated door apparatus of the type having 10 a vertical cylinder and piston and a pair of pivoted fire doors adapted to swing laterally and vertically, and to close by gravity. According to this feature of my improvement, a hand lever is provided having 15 a curved neck portion pivoted to the frame and engaging a pin on the piston of the motor whereby when the hand lever is swung downward the curved portion engages the pin and forces the piston downward, thus operating the door in the same 20 manner as when fluid pressure is admitted to the cylinder.

Another object is to provide improved 25 means for lubricating the pivots of the doors and the link connections.

In the accompanying drawings: Figure 1 is a front elevation of a door apparatus embodying my improvement; Fig. 2, a front view upon a larger scale, with the cover 30 plate removed and a portion of the cylinder indicated in section; Fig. 3, a plan; Fig. 4, a horizontal section taken substantially 35 through the pivot pin connection to the piston; Fig. 5, a transverse vertical section taken on the line 5-5 of Fig. 2; and Fig. 40 6, a detail sectional view taken through the pivot connections of the door and link, and showing the lubricating passages.

According to the construction shown in 45 the drawings, my improvement is illustrated in connection with a pair of doors, 5 and 5^a, mounted to swing laterally and vertically upon the respective pins, 6, and 6^a, supported in the door frame, 7, and operated by a fluid pressure motor comprising 50 a cylinder, 8, having flanges also supported on the pins or bolts, 6 and 6^a, and containing a piston, 9, bifurcated at its lower end and connected by links, 10 and 10^a, with 55 the respective doors, 5 and 5^a. The pivot pin, 11, by which the links are attached to

the piston, is extended upon the front side through a slot, 12, in the lower end of the cylinder casing for engagement with the hand lever, 13, which is provided with a 60 curved neck portion, 13^a, and pivoted at its end at 14, upon the cylinder casing.

In its normal position, the hand lever extends upward and outward in a plane substantially parallel with that of the doors, 65 and is adapted to be turned downward around the side of the door frame in the opening movement during which the curved portion, 13^a, engages the pin, 11, and forces the piston downward, thus opening the 70 doors. A roller may be mounted on the end of the pin, 11, to diminish the friction between the same and the curved portion of the lever.

For the purpose of holding the hand lever in its normal position or in partial or full open position, a latch, 15, is provided on the under side of the cover plate, 16, which is bolted to the cylinder casing at the front side for protecting the operating 80 parts. The lever is normally held at the top of the latch by means of a spring plunger, 17, mounted in a recess, 18, in the casing, and bearing against the side of the lever. Two other notches, 19 and 20, are 85 also provided in the latch for holding the lever at the partial and the full open positions respectively. The edges of these notches are beveled or inclined, as is also the upper edge of the lever, thereby preventing the lever from slipping out of the notches as the weight of the doors acting through the links, piston and pin tends to hold the lever in the notch when adjusted to either one of these positions.

When operating by hand, the leverage of the hand lever is gradually increased as it is turned downward from its normal position, since the pin, 11, rolls or slides along the under surface of the curved portion, 13^a, 90 and the distance between the centers of the pins, 11 and 14, gradually diminishes until the door reaches its full open position, thus materially increasing the power of the hand lever. In moving the hand lever from its 95 normal position, it is first pushed back against the plunger, 17, to compress the spring and release the lever from the latch. Then when the door has been opened the desired amount, the lever is pulled forward to 100 engage in either one of the notches.

When the door is operated in the usual

way by admitting fluid pressure into the cylinder, the hand lever does not move as the same is held in its normal position upon the latch by means of the spring plunger, 5 17, and the pin, 11, of the piston merely moves downward away from the lever without actuating the same.

Another feature of my improvement relates to the means for lubricating the piston 10 ton and the pivots of the doors and links, and comprises a lubricant chamber, 21, formed in the cylinder casing and having passages, 22 and 22^a, leading to the respective doors, and passage, 23, leading to the cylinder. The door, 5, is provided with a duct, 24, and a groove, 25, for feeding oil from passage, 22, to the pivot pins of the door and the link, and door, 5 has a duct, 24^a, and groove, 25^a, for supplying oil from 20 passage, 22^a, to its corresponding pivots. The recess, 18, may also communicate with the passage, 22, for lubricating the plunger, 17. In this way all of the moving parts are lubricated from a single chamber.

25 It will now be seen that I have provided a simple construction comprising a combined fluid pressure and hand operated door apparatus in which the piston is positively connected to the door and may be readily 30 operated by fluid pressure in the usual way or manually by the hand lever.

Having now described my invention, what I claim as new and desire to secure by Letters Patent is:

35 1. In a fire door apparatus, the combination of a door adapted to swing laterally and vertically, a vertical cylinder and piston having a positive connection with said door for opening the same by fluid pressure, 40 a pin projecting from said piston, and a hand lever having a curved portion engaging said pin for manually operating the piston.

2. In a fire door apparatus, the combination 45 of a pair of fire doors pivoted to swing laterally and vertically, a vertical cylinder and piston, links connecting the piston with

said doors, a pin projecting from the piston, and a hand lever having a curved portion engaging said pin for manually operating 50 the piston.

3. In a fire door apparatus, the combination of a pair of fire doors pivoted to swing laterally and vertically, a vertical cylinder and piston, links connecting the piston with 55 said doors, a pin projecting from the piston, and a hand lever pivoted at one end upon the casing and having a curved neck portion passing over said pin for manually depressing the piston.

4. In a fire door apparatus, the combination of a door, a cylinder, a piston having a positive connection with said door, for operating the same by fluid pressure, a pin projecting from said piston, and a pivoted hand 65 lever having a curved portion engaging said pin for manually operating the piston, the lever arm from the pivot to said pin diminishing as the lever is turned from its normal position whereby the leverage is increased.

5. In a fire door apparatus, the combination of a pair of fire doors pivoted to swing laterally and vertically, a vertical cylinder and piston, links connecting the piston with 75 said doors, a lubricant chamber carried by the cylinder and feed passages leading therefrom to the doors, said doors having feed ducts and grooves communicating with said passages for supplying lubricant to the pivots of said doors and links.

6. In a fire door apparatus, the combination of a door adapted to close by gravity, a cylinder and piston having a positive connection with said door for opening the same 85 by fluid pressure, a pin projecting from said piston, and a hand lever pivoted at its end and having an intermediate curved portion engaging said pin for manually operating the piston.

ALBERT G. ELVIN.
